(57) **CLAIM**

The ornamental design for a riser and umbilical clamp, as shown and described.

DESCRIPTION

FIG. 1 is a perspective view of a riser and umbilical clamp in accordance with the design;

FIG. 2 is a first side view of the riser and umbilical clamp in accordance with the design;

FIG. 3 is a second side view of the riser and umbilical clamp in accordance with the design;

FIG. 4 is a third side view of the riser and umbilical clamp in accordance with the design;

FIG. 5 is a fourth side view of the riser and umbilical clamp in accordance with the design;

FIG. 6 is a top plan view of the riser and umbilical clamp in accordance with the design; and,

FIG. 7 is a bottom plan view of the riser and umbilical clamp in accordance with the design.

Any broken lines present in the drawings are for illustrative purposes only and form no part of the design to be patented.
